UNITED STATES PATENT OFFICE

IRBY M. WHELAN, OF BIRMINGHAM, ALABAMA

DESIGN FOR A COMBINED GAME AND SMOKER'S APPLIANCE

Application filed June 27, 1930. Serial No. 36,197. Term of patent 14 years.

To all whom it may concern:

Be it known that I, IRBY M. WHELAN, a citizen of the United States of America, residing at Birmingham, in the county of Jefferson and State of Alabama, have invented a new, original, and ornamental Design for a Combined Game and Smoker's Appliance, of which the following is a specification, reference being had to the accompanying drawing, forming part thereof.

The figure is a perspective view of a combined game and smoker's appliance showing my new design.

I claim:

The ornamental design for a combined game and smoker's appliance, as shown.

IRBY M. WHELAN.
